Primary Examiner — Mark Goodwin(74) *Attorney, Agent, or Firm* — Egbert Law Offices, PLLC(57) **CLAIM**

The ornamental design for a lawn mower, as shown and described.

DESCRIPTION

FIG. 1 is a front perspective view of a lawn mower showing my new design.

FIG. 2 is a side view thereof;

FIG. 3 is an opposite side view thereof;

FIG. 4 is a front view thereof;

FIG. 5 is a rear view thereof;

FIG. 6 is a top view thereof;

FIG. 7 is a bottom view thereof; and,

FIG. 8 is a rear perspective view thereof.

The features presented in broken lines represent unclaimed portions of the lawn mower and form no part of the claimed design.
